UNITED STATES PATENT OFFICE.

GUSTAV STROHAKER, OF WALLINGFORD, CONNECTICUT, ASSIGNOR TO
THE WATROUS MANUFACTURING COMPANY, OF SAME PLACE.

DESIGN FOR A HANDLE FOR SPOONS, FORKS, &c.

SPECIFICATION forming part of Design No. 28,923, dated June 28, 1898.

Application filed May 23, 1898. Serial No. 681,512. Term of patent 7 years.

to all whom it may concern:

Be it known that I, GUSTAV STROHAKER, of Wallingford, in the county of New Haven and State of Connecticut, have invented a new design for a Handle for Spoons, Forks, &c.; and I do hereby declare the following, when taken in connection with the accompanying drawing and the letters of reference marked thereon, to be a full, clear, and exact description of the same, and which said drawing constitutes part of this specification and represents a face view of a spoon-handle embodying my design.

This invention relates to a design for a handle for spoons, forks, and like articles of table-service; and the design consists in the configuration and ornamentation as hereinafter described, and shown in the accompanying illustration.

The handle gradually expands from its lower end upward to a point about half-way the length of the handle, where it expands, then slightly contracts, and then again expands to form the upper end or tip of the handle.

Starting from a point near the lower end of the handle, a groove A is formed upon each side of the handle, which follows the contour of the handle and gradually expands in width until it reaches the first expansion of the handle, where it merges into foliated scrolls B, from which spring incurving scrolls C, which are in turn surmounted by and merge into an elaborate scroll ornamentation surmounted by a shell D, which forms the tip E of the handle. Within this scroll ornamentation a plain panel F extends throughout the length of the handle, all as shown in the accompanying illustration.

I claim—

The design for a handle for spoons, forks or similar articles as herein shown and described.

In testimony whereof I have signed this specification in the presence of two subscribing witnesses.

GUSTAV STROHAKER.
